UNITED STATES PATENT OFFICE.

PERRY OKEY, OF COLUMBUS, OHIO.

HEAT-ENGINE.

1,343,577.

Specification of Letters Patent. Patented June 15, 1920.

Application filed March 28, 1918. Serial No. 225,317.

To all whom it may concern:

Be it known that I, PERRY OKEY, a citizen of the United States, residing at Columbus, in the county of Franklin and State of Ohio, have invented certain new and useful Improvements in Heat-Engines, of which the following is a specification.

This invention relates to a heat engine which produces mechanical work by utilizing the heat contained in the atmosphere as a primary source of energy. My invention employs a working fluid which is made to vary in density or pressure by a temperature difference created and maintained by the inherent heat of the atmosphere and by the capacity of the atmosphere for absorbing water vapor. The working fluid may be one of the so called true gases or the vapor of a liquid and the working cycle may be that of a true gas or a vapor cycle in which the substance is alternately vaporized and condensed to its liquid. In either case the working fluid merely acts as the agent which absorbs heat from the atmosphere, converts a part of such heat into mechanical work, and rejects the remainder of the heat back into the atmosphere through the medium of water vapor.

An embodiment of my invention when using a liquified gas as the working medium is shown in the accompanying sheet of drawings in which similar characters of reference designate corresponding parts, and in which,

Figure 1 represents a heat engine embodying all the elements of my invention, and,

Fig. 2 is a section taken on line 2—2 of Fig. 1.

In these drawings, the boiler is represented by the reference numeral 1 and this boiler is provided with a plurality of fins or ribs 2 or some similar structure whereby heat may be readily absorbed from the atmosphere. The condenser is represented by the reference numeral 3 and is provided on its exterior surface with a covering of fibrous material such as wicking 4 which latter is in communication with a supply of water 5 confined within the cup shown at 6. The boiler 1 is in communication with a power element or prime mover through the medium of the connection of conduit 7 which latter is provided with a valve 8. The prime mover itself has been illustrated as a turbine wheel 9 mounted upon a shaft 10 which projects out through the hermetically sealed

housing 11 which is mounted upon the open top of the condenser 3 to be in communication therewith as is shown. The shaft 10 is shown as being provided with a pulley 60 wheel 12 to serve for transmitting its motion to any desired source and the housing itself is arranged to receive the nozzle 13 so that the latter will be in proper working relation with respect to the turbine wheel 65 and also in communication with the conduit 7. After the gas or vapor flowing through the conduit 7 has been directed against the turbine wheel, it may enter the top of a condenser 3 in the manner illustrated. The bottom of this condenser and the bottom of a boiler are also in communication with each other by means of the conduit shown at 14 which latter is provided with a covering of insulating material 15 to prevent the radiation of heat as much as is possible.

The method and manner of operation is as follows: A suitable working fluid such as liquid sulfur dioxide, anhydrous ammonia, or any liquid which is convertible into a gas or vapor at ordinary temperatures is utilized. The air is exhausted from the entire system through the valve shown at 16 and the working fluid is then introduced into the boiler by means of this same valve. 85 A sufficient quantity of this fluid is introduced so that a portion of the system such as the boiler 1 will contain the fluid in liquid form while its vapor fills the remaining space, the fluid itself forming a pressure in 90 the system for preventing all of the liquid from being converted into a vapor at the particular temperature of the atmosphere at which the fluid is introduced. The cup 6 is filled with water which spreads over the 95 surface of the condenser because of a fibrous covering by capillarity. Under normal conditions, such as when the atmosphere is above 32 degrees F. and when the relative humidity is less than 100% this water will 100 evaporate from the surface of the condenser and, inasmuch as heat is required to effect such evaporation, it follows that a portion of such heat is abstracted from the condenser which reduces its temperature and the temperature of its contents and therefore causes a condensation of a part of the vapor therein and a reduction of the vapor pressure necessarily follows. A difference now exists between the vapor pressure in the condenser 110 which is lower in temperature than the atmosphere and the vapor pressure in the

boiler which has a temperature equal to that of the atmosphere, it being understood that the orifice in the nozzle 13 is comparatively small. The condensed vapor leaving the 5 condenser and entering the boiler as a liquid having a temperature lower than that of the atmosphere absorbs heat from the atmosphere through the boiler walls and is raised in temperature until it approaches or equals 10 that of the atmosphere. The pressure of the vapor above the liquid in the boiler corresponds of course to the temperature of the liquid and is necessarily higher than that in the condenser and this higher pressure 15 causes a flow of vapor through the turbine to the condenser, mechanical work being developed by the turbine during such transfer. The difference of vapor pressure also causes a difference of levels of the liquid in the 20 boiler and that in the conduit 14 leading from the condenser to the boiler and this difference acts in lieu of a pump for feeding the boiler, but this arrangement is not absolutely essential and in fact, could not 25 be used if the condenser were placed below the level of a boiler, in which case a pump will be required for the purpose.

It will be noted, therefore, that the processes are continuous, heat being rejected 30 from the condenser to the atmosphere through the medium of the evaporation of water causing a continuous condensation of vapor in the condenser, and a continuous absorption of heat from the atmosphere by 35 the boiler, equal in value to that rejected by the condenser, less, however, the amount which is transformed into mechanical work by the turbine.

Stated in another way, a difference in temperature is maintained between the intake 40 and exhaust sides of a prime mover which causes the working vapor to be continuously condensed to its liquid on the exhaust side, and the liquid to be continuously evaporated 45 into its vapor on the intake side, both of which functions are due to and are caused by properties existing in the atmosphere whereby additional heat may be absorbed by it through the vehicle of water vapor 50 while heat is being given up by another portion of it though being at the time in the same state of temperature and humidity. Such interchange of heat is utilized in the production of mechanical work through the 55 working vapor acting upon the vanes of the turbine wheel after expanding in the nozzle 13 during its change from initial to final pressure.

Instead of using a liquefied gas as a working 60 fluid, air or any other so called perfect gas may be selected, a fixed weight of it being confined and caused to alternately absorb and reject heat from and to the hot and cold sides of an apparatus such as has been 65 described, the variation of pressure created

by the temperature changes, and consequently density changes, of the confined gas being made to perform work.

From the foregoing description taken in connection with the accompanying sheet of 70 drawings, it will be apparent that I have provided a heat engine which utilizes the inherent heat of the atmosphere as a source of energy to produce mechanical work. This is effected by the rejection of heat to 75 the atmosphere through the evaporation of water and by the absorption of heat by the boiler by direct contact with the atmosphere. When once the engine is set in operation, it will continue in operation in 80 definitely by using the working fluid over and over again so long as water is supplied to the cup 6 and so long as the atmospheric temperature is above 32 degrees F. and the relative humidity of the atmosphere is below 85 100%.

During periods of high humidity or temperature below 32 degrees F., power may be generated by supplying artificial heat to the boiler. The energy represented by the 90 latent heat of fusion of ice or snow may also be utilized by permitting these substances to abstract heat from the condenser while heat is being absorbed from the atmosphere by the boiler. Similarly, a difference in temperature between the atmosphere and a body of water such as a river, lake or ocean may be utilized for work by the absorption and rejection of heat as described.

What I claim is:

1. A heat engine comprising an inclosed cycle of parts in which a working fluid is confined, said fluid being convertible from a liquid into a vapor at atmospheric temperatures, said cycle including a condenser, a boiler positioned below said condenser, a conduit of relatively small diameter connecting the lower ends of said condenser and boiler, a second connection between the upper portions of said condenser and boiler, and a work producing element situated within said second connection, the pressure of the working fluid in said boiler being greater than that in the condenser whereby the level of the fluid in said boiler will be appreciably lower than that in the conduit, thus permitting a positive gravitational flow of the fluid from said condenser and into said boiler.

2. A heat engine comprising a working fluid which is convertible into a vapor at atmospheric temperatures, a boiler and a condenser in which the working fluid is confined, said condenser being situated on a plane substantially above said boiler, means for transferring the working fluid from said condenser to said boiler by gravitational flow, said means being of lesser diameter than said boiler and responsive to the variation

in the respective pressures of the condenser and boiler to maintain the liquid in said boiler on a lower plane than in said means, a connection between the said boiler and condenser for the flow of the working fluid in the vapor state, and a power developing element interposed in the last named con-

nection and capable of utilizing the work available by the subjection of the working fluid to the different temperatures effected through the use of said boiler and condenser.

In testimony whereof I affix my signature.
PERRY OKEY.
